United States Patent Office

Des. 221,631
Patented Aug. 31, 1971

221,631

BUILDING

Charles F. McAlpine, Fort Lauderdale, Fla., assignor to Ranch House of America Inc., Fort Lauderdale, Fla.

Filed May 8, 1970, Ser. No. 22,886

Term of patent 14 years

Int. Cl. D25—04

U.S. Cl. D13—1

FIG. 1.

FIG. 2.

FIG. 3.

FIG. 4.

FIG. 5

FIG. 1 is a front elevational view of the building, embodying my design;

FIG. 2 is a side elevational view thereof;

FIG. 3 is an elevational view of the side opposite the front thereof;

FIG. 4 is a back elevational view thereof; and

FIG. 5 is a top plan view thereof.

I claim:

The ornamental design for a building, substantially as shown.
